LOAD LIMITER FOR SPEED GOVERNORS

Floyd H. Sweet, Euclid, Ohio, assignor to The Marquette Metal Products Company, Cleveland, Ohio, a corporation of Ohio

Application October 29, 1952, Serial No. 317,543

7 Claims. (Cl. 121—42)

1

The invention relates to improvements in load or torque limiters for engines controlled by governors. The objects include provision of an improved hydraulic relay governor load limiter which operates as a combined function of load as represented by the position of a fuel regulating element of the governor and of actual engine speed; and to a centrifugally acting load limiting mechanism of a governor requiring very small space and flyweight mass, yet which is highly sensitive to engine speed changes requiring its operation and is otherwise efficient and free from hunting or cycling during its action to limit load or torque. Other objects include various specific improvements in governor load limiting as will appear from the following description of a preferred embodiment.

In the drawing, Fig. 1 is a schematic view of a typical hydraulic relay governor incorporating the invention; Fig. 2 is a fragmentary longitudinal, vertical sectional full scale view of a speed measuring and connected fluid valving hydraulic mechanism forming part of an actual physical embodiment.

The main governor unit, as shown in Fig. 1 (representing a typical hydraulic relay speed governor mechanism), has a casing A, containing an engine-speed-change-detector, including flyballs B, a speeder spring C and a pilot valve the movable part of which is plunger D (sometimes hereinafter referred to as the governor pilot valve). The pilot valve controls the operating effect of substantially constant pressure fluid (governor oil as from a pump and accumulator, not shown, admitted by line or passage F) on a servomotor, represented by power piston H. Passage F is continually connected to the left hand end of the servomotor. Passages G and G' between the pilot valve and the right hand end of the servomotor are normally interconnected. Governor oil, in the illustrated equilibrium or steady-state position of the pilot valve is trapped by that valve in lines G and G' in contact with relatively larger area (face J) of the power piston H whose smaller area (face I), as indicated above, is continually subjected to governor oil pressure through line F. Line F has a branch F' which is normally closed.

To cause "fuel-on" (leftward) movement of the power piston H the pilot valve plunger (by lowering as in response to diminished engine speed, thus opening port E) admits governor oil through G, G' to the right hand cylinder chamber of the power piston; and, to cause "fuel-off" or reverse piston movements, the pilot valve

2

plunger is raised and then spills trapped oil at pilot valve sump connection port S.

A hydraulically acting feedback (temporary speed droop or "compensation") system between the governor power piston H and its pilot valve D is diagrammatically represented as comprising an actuating displacement pump N; oil passage O; receiving piston P which is spring-connected to the pilot valve, and a needle valve R for adjusting leakoff. The system is substantially that of A. Kalin Patent 2,219,229, dated October 22, 1940.

The governor, as shown, has a known type of speed setting mechanism including a lever 10 suitably connected between its ends to the speeder spring C. End portion 10a of the lever is subject to speed setting operation (vertical movement) as by a hand knob or suitable power means not shown. End portion 10b is connected for similar movement by a speed droop linkage, forming no essential part of the present invention but which, as partially shown, includes a bell crank 11 supported on a fixed pivot 12, one arm of the bell crank being connected to lever 10 and the other, at vertically adjustable pin 13 on said other arm, being connected to a power-piston follower lever 15 for movement by that lever through its connection with the power piston at 16. In the illustrated position of pin 13 that pin is concentric with a fixed pivot (not shown) of the follower lever on the governor case. The linkage, which is according to A. Kalin Patent 2,341,384, is thus shown as set for zero speed droop.

In the type of the Marquette Metal Products Company governor, essentially as shown in the last above mentioned patent, the power piston follower lever 15 is so located as to form a convenient means for operating a load limiting valve T thereof (shown at the far right in Fig. 1) partly as a function of power piston movement in the "fuel-on" direction thereof, Fig. 1.

A plunger 20 of valve T controls ports 21 in sleeve 22 (which ports, as shown, are connected to trapped fluid line G) to close line G when plunger 20 is depressed a predetermined distance. At nearly the same time as ports 21 are closed by downward movement of valve plunger 20 a lower land of the plunger opens line portion G' at sleeve ports 23, to commence spilling the fluid trapped in contact with larger piston face J through a sump-connected passage S'.

Valve plunger 20 of valve T is arranged for operation by a floating lever 25 having a variable fulcrum 26 (on a stem portion of a servomotor

piston 28, to be described presently); and the leftward end of lever 25 is connected for movement by the power piston follower lever 15 through a rack and cam mechanism U. Servo piston 28 is caused to operate as a function of engine speed through a pilot valve plunger 29 as will be described later.

Mechanism U comprises, as shown in Fig. 1, a slidably mounted toothed rack 30 biased to the right against a stop 30' by a relatively strong spring 31; an operating abutment finger 32 on the follower lever which engages a pin 33 on the rack; an angularly movable cam 35, and a pinion 36 normally rigid with the cam and having its teeth in constant mesh with those of the rack 30. A slot 38 in the cam embraces a pin 39 projecting from the floating lever 25; and the cam slot is so designed that, after "fuel-on" movement of the power piston H through its no-load or normal idling range (from "no-fuel" position to midposition, for example, as would be determined generally by proper adjustment of abutment finger 32, shown as locked in place on lever 15 by cap screw 32', Fig. 1) the pin 33 of the rack is engaged by abutment finger 32, and then each unit increment of power piston travel in the "fuel-on" direction operates to raise the left hand end of the floating lever by a proportional unit increment. That, as will be apparent, can tilt the lever about its fulcrum 26 to depress the valve plunger 20 to close load limit valve ports 21 and open spill ports 23.

Whether or not the load limiting valve action just above outlined occurs is contingent upon actual engine speed as measured by auxiliary flyball and connected servo piston valve mechanism V, which mechanism determines the position of floating lever fulcrum 26 on servo piston 28. Mechanism V is capable of preventing load limiting action of valve T from taking place whenever the engine speed is sufficiently high to enable safe or desirable increase of fuel to the engine.

Engine speed measuring (etc.) mechanism V, as shown best in Fig. 2, includes flyball assembly 5 on a rotary ballhead 6 which is continually connected in a suitable manner for rotation by the governor drive shaft (not shown). The flyballs 7 and their centrifugal-force-opposing or loading spring 8 are designed so that the flyballs assume a different position for each engine speed above the maximum no-load speed, i. e. idling speed or through any other desired speed range. The flyball reactance force of spring 8 is adjustable by means of a threaded cap 9 in a spring-housing sleeve portion 40 of the ballhead 6. The spring 8 is maintained under predetermined axial strain between the cap 9 and a thrust plate 41 which is threaded to a push rod 42 freely slideable in the ballhead.

The pushrod 42 of the auxiliary flyball mechanism V, for initiating downward pressure-actuated movement of the servo piston 28, acts directly against a head portion 29' of servo piston pilot valve plunger 29, beneath which head portion a light spring 44 biases said pilot valve plunger upwardly, e. g. returns the plunger toward the ballhead assembly, as when the reactance force of spring 8 is overcome by centrifugal force acting on the auxiliary flyballs.

Mechanism V is enabled to have a very small flyball mass and, in general, be of compact design through use of servo piston 28 and small diameter, freely movable pilot valve thereof. The effective opposing forces of springs 8 and 44 on

pilot valve plunger 29 cause the necessary movement of that plunger and the latter valves operating fluid to move the servo piston, thus to shift the floating lever fulcrum 26 as a function of engine speed. The pilot valve plunger 29 is always exposed to negligible pressure at both ends (bottom end through sump-connected passage S') and the servo piston mechanism is designed for fluid pressure operation essentially as is the governor power piston H, through governor fluid supply at F' under servo piston pilot valve control at ports 51 and 52. Trapped oil in space 54 above the servo piston proper is spilled at ports 51 by upward pilot valve plunger movement to cause upward piston travel due to pressure in lower piston cylinder space 55, and governor oil is admitted to space 54, to cause lowering of the piston, by downward movement of the valve such as will open ports 52. Thus the piston 28 is power-operated and caused to follow all pilot valve movements, and the resistance to movement of the pilot valve plunger 29 is only that of friction between it and its small bore.

The engine speed measuring flyball mechanism 5 can, if desired, be rendered ineffectual, without interfering with the operation of the main governor in controlling the engine, by removing the cap 9 and spring 8 from housing 40 and then—with one flyball 7 suitably held in its maximum outward position as against the stop provided by the lower end of housing 40—replacing the cap without the spring in a screwed in position of the cap such that its stem portion 43 abuts the top end of pushrod 42. The relatively weak return spring 44, acting through the head plate 29' of pilot valve 29 on the pushrod, then holds the flyballs in their outwardmost positions; and, by reason of the continually elevated pilot valve and consequent fluid pressure follow-up action on its servo piston, the fulcrum 26 of lever 25 holds the valve plunger of mechanism T out of range of its controlled ports. The point in the travel of fuel-metering servomotor piston H in the "fuel-on" direction at which valve plunger 20 of valve T interrupts further "fuel-on" movement at a predetermined engine speed is precisely adjusted to meet engine and load requirements as a final operation after installation of the governor on the engine. To render the precision adjustment means readily accessible through the top of the governor case (assuming the usual cover partly suggested at A', Fig. 1, is not yet in place) said means is arranged to function by varying the port-controlling relative position of the plunger 20 and sleeve 22 of valve T. As illustrated the sleeve 22 is screw threaded at 22' into the governor case A, the sleeve has gear teeth at 62, and a suitably supported upright shaft 60, manipulable as by a screw driver or other tool, has teeth 61 in constant mesh with those of the valve sleeve. Shaft 60 has a locking spring 63 to maintain the final adjustment. The minimum engine speed at which a particular load can be imposed upon the engine is separately adjustable through the top of the governor case by turning the cap 9 in ballhead mechanism 5 to vary the acting force of the flyball loading spring 8. The cap is also provided with suitable adjustment maintaining means, not shown, preferably a lock wire.

In operation, as soon as the power piston H has been moved by hydraulic relay governor action in the "fuel-on" direction into its preadjusted load carrying range, further power piston movement in that direction tends, through cam

mechanism U, to depress plunger 29 of valve T, closing ports 24 and arresting further power piston movement in that direction; but, so long as the actual engine speed is appropriate to load, the auxiliary flyballs of mechanism V maintain such positioning of floating lever pivot 26 that the servomotor-imparted cam action of mechanism U is ineffective. The design and adjustment of the mechanism as a whole is such that supply of operating fluid to the governor servomotor through line G becomes blocked at ports 21 of valve T when the maximum load is imposed at a predetermined speed, thus preventing application of additional loading at that speed.

The following features of the present governor load limiter construction co-operate in preventing hunting such as is apt to occur with a centrifugally acting load limiter of the general type shown:

1. The servo piston pilot valve plunger 29 requires almost negligible operating force; hence the position of floating lever fulcrum 26 is always truly representative of existing engine speed (negligible lag).

2. Spilling of operating fluid from the governor servomotor necessarily results in a gradual movement of the power piston toward "no-fuel" position because, as the decelerating flyballs 7 commence to cause opening of spill ports 23, the thus initiated "fuel-off" movement of the power piston tends to close them (essentially the same feedback action as the servo piston 28 has).

3. Servomechanism-actuated cam 35 of mechanism U acts positively in two directions on the floating lever 25 with negligible backlash, to that any reversal of governor power piston movement direction is immediately translated into repositioning of the plunger of valve T. Spring 31 of rack 30 is strong enough always to insure rightward movement of the rack and counter-clockwise movement of the cam 35.

Referring to the portion 38' of the slot of cam 35 which is concentric with the mounting axis of the cam, the cam is so adjusted on its supporting shaft that the follower pin 39 on the floating lever 25 encounters the concentric portion slightly before the power piston H, in its "fuel-on" movement, has arrived at the proper full load position. Thereby, when the engine is operating at rated load and speed, the main governor speeder and pilot valve mechanisms are in full control, and a certain range of servomotor movement necessary for maintenance of set speed despite minor torque variations is permitted without interference by the load limiting mechanism hereof.

I claim:

1. In a hydraulic relay speed governor for engines, the governor having speed setting means acting through speed-change-responsive pilot valve means to cause engine-fuel-regulating movement of a servomotor, a load limiting valve between the pilot valve and a pressure chamber of the servomotor, which chamber receives fluid under control of the pilot valve to cause "fuel-on" movement of the servomotor, the load limiting valve including a port-closing and port-opening member operable to block flow of fluid to said chamber and to spill fluid from said chamber, a floating lever connected to said member to move it to said port-closing and port-opening positions, servomotor-connected means including a variable-fulcrum-establishing means for the lever for enabling such movement of the

lever by the servomotor, an engine-speed-measuring means connected for operation by the engine through the governor and having an output element in the form of a valve plunger, a servo piston having fluid ports controlled solely by movement of the valve plunger in opposite directions to cause the piston to follow all movements of the valve plunger, and another variable fulcrum for the lever operatively connected for movement of the lever by the servo piston in the same plane as the lever is moved by the servomotor-connected means, whereby load limiting operation on the servomotor by the load limiting valve is a combined function of servomotor position and engine speed.

2. The mechanism according to claim 1, wherein the servomotor-connected variable-fulcrum-establishing means comprises a twin surface cam connected for to-and-fro-movement by or with the servomotor and a follower on the lever engaging both surfaces of the cam for positive movement of the lever by the cam in opposite directions.

3. The mechanism according to claims 1 and 2 wherein the cam surfaces include dwell portions engaged by the follower when the servomotor has moved to a predetermined position in the "fuel-on" direction approximately appropriate to full load.

4. The mechanism according to claim 1, wherein the speed measuring device comprises loading-spring-biased flyballs operatively connected to the valve plunger of the servo-piston by a pushrod which can move away from that plunger without carrying the plunger with it, and the servo piston valve plunger has a return spring connected to move both it and the push rod in a direction opposite that in which the loading spring acts on the pushrod.

5. In a hydraulic relay speed governor for engines, the governor having speed setting means acting through speed-change-responsive pilot valve means to cause engine-fuel-regulating movement of a servomotor, a load limiting valve between the pilot valve and a pressure chamber of the servomotor, which chamber receives fluid under control of the pilot valve to cause "fuel-on" movement of the servomotor, the load limiting valve including a plunger slidable in a valve sleeve which sleeve has a port closed by the plunger to block flow of fluid to said chamber and another port opened by the plunger to spill fluid from said chamber, a floating lever connected to said plunger to move it to said port-closing and port-opening positions, servomotor-connected means including a variable-fulcrum-establishing means for the lever for enabling such movement of the lever by the servomotor, an engine-speed-measuring means connected for operation by the engine through the governor and having output means connected to another variable fulcrum for the lever for moving the lever in the same plane as it is moved by the servomotor-connected means, whereby load limiting operation on the servomotor by the load limiting valve is a combined function of servomotor position and engine speed, and adjusting means operable on the load limiting valve sleeve to move it axially relative to its plunger, thereby to enable the servomotor to render the load limiting valve effective and ineffective in predetermined different portions of the total range of movement of the servomotor.

6. The mechanism according to claim 5, wherein the load limiting valve sleeve is in screw-threaded relation to its support, and the adjusting

means is an angularly movable member connected to the sleeve through constantly meshing gear teeth.

7. In a hydraulic relay speed governor for engines arranged in an upright casing, the governor having speed setting means acting through speed-change-responsive pilot valve means to cause engine-fuel-regulating movement of a servomotor piston in an approximately horizontal direction, a load limiting valve between the pilot valve and a pressure chamber of the servomotor, which chamber receives fluid under control of the pilot valve to cause "fuel-on" movement of the servomotor, the load limiting valve including a port closing and port opening upright plunger in a mating sleeve, operable to block flow of fluid to said chamber and to spill fluid from said chamber, a generally horizontal floating lever connected to said plunger to move it to said port-closing and port-opening positions, servomotor-operated means including an upright lever continually connected to the servomotor piston, a

cam operatively connected with the upright lever and a cam follower on the floating lever bearing on the cam, an engine-speed-measuring flyball mechanism connected for operation by the engine 5 through the governor and having a vertically acting output element constituting another variable fulcrum for the lever and connected therewith, whereby load limiting operation on the servomotor by the load limiting valve is a combined 10 function of servomotor position and engine speed, and means accessible through the top of the upright casing and connected to the load limiting valve sleeve in a manner to enable relative adjustment of the plunger and sleeve axially.

FLOYD H. SWEET.
